UNITED STATES PATENT OFFICE.

ERLING MEIER, OF CHRISTIANIA, NORWAY.

CARBURETER.

1,178,866.

Specification of Letters Patent. Patented Apr. 11, 1916.

Application filed June 22, 1914. Serial No. 846,542.

To all whom it may concern:

Be it known that I, ERLING MEIER, a subject of the King of Norway, residing at Christiania, Norway, have invented certain new and useful Improvements in Carbureters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in carbureters, and the object of the invention is to facilitate the starting of the motor and improve the evaporation of the liquid combustible. These objects are attained chiefly by means of a cup or vessel surrounding the nozzle outlet, which cup will be filled with liquid fuel, when the motor is not working, or when it is working slowly, and will cooperate with the air intake in such a way that when the motor is started the fuel in the said cup will be volatilized by means of the air sucked in past the cup.

In the accompanying drawing Figure 1 is a central vertical section through a carbureter constructed according to my invention, and Fig. 2 is a plan thereof.

The liquid fuel passes from a float chamber (not shown) through a passage 5 to the nozzle 6 of the carbureter, which is controlled as usual by means of the needle valve 7.

The nozzle 6 is surrounded by a cup or vessel 8. When the motor is resting and before it is started, the liquid fuel is allowed to flow into the cup 8. Inside the cup 8 is placed an annular perforated plate 16, which is connected by means of links 17 to levers 18. The latter are provided at their

free ends with vanes or plates 19 obstructing the air passage around the cup 8. When the motor is started and air is sucked in through the inlet 10 as indicated by the arrows, the vanes will be pressed upward and will in turn press the plate 16 down into the cup. The liquid fuel in the cup will then be pressed as a spray through holes in the said plate and will be taken up by the suction and volatilized.

I claim—

1. In a carbureter, a jet device for combustible, a cup surrounding the same, and means to form the combustible in the cup into jets, said means actuated by the air for vaporizing the combustible.

2. In a carbureter, a nozzle, a cup surrounding the same, a perforated plate in said cup normally above the liquid level therein, and means actuated by the air for vaporizing the combustible, to force said plate down into the combustible and form jets by said perforations.

3. In a carbureter, the combination of a nozzle for the liquid, a cup surrounding the nozzle and adapted to contain liquid fuel when the motor is resting, a perforated plate adapted to move vertically in said cup, pivoted levers connected to said plate and carrying on their free ends vanes which are acted upon by the air sucked in so as to press the plate into the cup and produce a spray of liquid through the holes in said plate.

In testimony that I claim the foregoing as my invention, I have signed my name in presence of two subscribing witnesses.

ERLING MEIER.
